UNITED STATES PATENT OFFICE.

ORNAN S. COOK AND HENRY A. GALE, OF FITCHBURG, MASSACHUSETTS.

BLOCK PLANER.

Application filed November 21, 1921. Serial No. 516,561.

To all whom it may concern:

Be it known that we, ORNAN S. COOK and HENRY A. GALE, both citizens of the United States, residing at Fitchburg, in the county 5 of Worcester and State of Massachusetts, have invented a new and useful Block Planer, of which the following is a specification.

This invention relates to a machine for 10 planing the block of a sole or other leather cutting machine. The principal objects of the invention are to provide a simple planing device adapted to be conveniently mounted on a sole or other die cutting 15 machine, in such position as to ensure the dressing off of the top of the block in a perfect plane; to provide a simple and practical frame for the rotary cutters so arranged and mounted that it can be moved across the 20 block by hand and removed from the sole cutting machine without danger of getting it out of position to dress off the top of the block in an accurate manner; and to provide improvements in the way of supporting the 25 frame or carriage and other features of construction.

Reference is to be had to the accompanying drawings in which

Fig. 1 is a front view of a sole cutting 30 machine showing a preferred embodiment of this invention applied thereto.

Fig. 2 is a transverse sectional view on the line 2—2 of Fig. 1 showing the planer in elevation; and

Fig. 3 is a plan of the planer supporting 35 frame removed from the sole cutting machine.

I have shown the invention as applied to a leather cutting machine 10, having a block 40 11 composed of pieces of wood arranged with the grain vertical and held in position on the bed of the machine in any of the ordinary ways.

The machine also is provided with the 45 usual beam 12. In operation the leather is spread on the top of the block and the dies arranged on the leather. The operation of the machine is to force the dies through the leather against the surface of the block by 50 bringing the block and the beam 12 toward each other by the movement of either one, as may be desired. Naturally this is severe service for the upper surface of the block and it becomes scarred and worn unevenly.

Heretofore, the ordinary method of dressing off the worn surface was to cut it down

by means of rotary tools supported and manipulated by hand, but rotated by power. The natural tendency of such a device was to emphasize any depressions that might exist in the face of the block and there was no means except the judgment and skill of the operator to cause them to cut in a plane and retain the original flat surface of the block. This invention is designed to take advantage 60 of certain features of the leather cutting machine and use them to correct deficiencies of the ordinary block dressing device above described.

It will be observed, of course, that the bottom of the beam 12 is in a plane which necessarily is parallel with the upper surface of the block, when the block is new. I take advantage of this fact and use the beam for supporting the planer. The planer comprises a frame made up of four round or other shaped rods 14 and 13, connected at their corners to form a square supporting frame. The two side members 14 of this frame are provided with means for attaching the frame to the beam. This comprises on each side a stationary jaw 15, and a movable jaw 16. The stationary jaw can be pinned by the means of pins 17, in any one of a number of positions on the side member 85 14. This is provided for by the perforations 18, for receiving this pin. Each of the jaws 16, is mounted on a support 19 and has an adjustable screw 21, which is adapted to bear on the side member 14, to force the jaw 90 down and clamp it in position. The two jaws 15 and 16 are adapted to engage on opposite flanges of the beam 12 and the frame in this way is secured on said beam in any set position along it with its upper surface in close contact with the bottom surface of the beam.

The end members 13 of the frame are provided with transverse teeth 23 on the bottom, so that they constitute racks. Arranged to slide on these racks are a pair of brackets 24, each having a pair of opposite perforations resting on the smooth continuous convex upper surfaces of the rods 13, which constitute guides. Mounted in bearings in one end of each bracket, is a shaft 25 and extending clear across. The end of this shaft is squared off and provided with a handle or crank for turning it. The shaft is also provided with two pinions 26, fixed to it at each 100 end and meshing with the racks. The rotation of the shaft 25 thus moves the two

brackets 24 and everything carried by them along the frame. Stops 29 are provided for limiting this motion. The two brackets 24 are connected by cross pieces 28. The four pieces 24 and 28 constitute a sidewise movable frame.

The cross pieces 28 are provided with ways 27 in which is mounted a slide 30. This slide is in the form of a plate, the opposite edges 10 of which rest on and slide along the ways as will appear.

Depending from this plate is an electric motor 31, the casing of which is secured to the bottom of the plate. The motor has a 15 shaft 32 extending through it, mounted in suitable bearings at the ends of the casing and on one, or preferably both, ends of the shaft is a Lamson saw 33. These two saws are designed for planing off the top of the 20 block 11.

On the slide 30 is supported a casing 35 for a fan 34. This fan is provided with a shaft 36, on which the fan itself is mounted and on which is a pulley 37. This shaft 36 25 receives its power from the shaft 32 through a pulley 38 thereon and belt 39. The fan is provided with an inlet pipe 40 divided into two branches, each having an inlet opening 41, located adjacent to the bottom 30 of the respective saws 33. Sawdust, or the like, is brought in through the pipe 40 and into the fan and is discharged through the outlet 42. The motor casing is also provided with a handle 45 rigidly fixed to and 35 depending from it.

It is to be observed that the frame can be mounted any where along the beam 12, and that when fixed, the saw carriage 24—28, can be moved along this frame in the 40 same direction, that is, longitudinally of the beam. This provides for the ordinary adjustment in that direction. In this device the motor is started and the slide 30 is moved along the ways 27 from front to back 45 or from back to front, to plane the top of the block through-out an area the width of the saw and extending clear across the block. Then the shaft 25 is turned to shift the saw carriage along the necessary distance and the slide is then moved back and forth again. This is repeated until the area covered by 50 the range of adjustments between the two stops 29, has all been planed. This is so designed that each one of the saws will cover more than half the distance between the stops, so that no second setting is required for any area within the limits of the operation of the carriage. When this much is done the whole outside frame 14—13 is 55 moved along the beam by releasing the two jaws 16, and then sliding it along by hand and finally tightening these jaws. Then the above described operation is repeated.

It will be seen that the beam 12 itself, 60 the lower surface of which is plane, conse-

quently serves as a guide for the saws, consequently no matter whether the block is worn or not, or how unevenly it may be worn on top, the result is a perfectly plane surface, provided the distance between the beam and block is adjusted so as to enable the saws to cut deep enough. The human element is entirely done away with so far as the contour of the plane surface is concerned and an accurate result is secured. The surface of the block is necessarily exactly parallel with the lower surface of the beam. All necessary adjustments are provided for and the motor slide with its saws and fan can be removed from the rest of the frame by pulling it out through the ends of the ways 27, by means of the handle 45. As this relieves the supporting frame of a good part of its weight, this is usually done when it is desired to remove the device from the cutting machine, although the whole device can be removed as a unit if desired.

Although we have illustrated and described only a single form of the invention and shown it as applied to only one type of leather cutting machine, we are aware of the fact that modifications can be made therein by any person skilled in the art, without departing from the scope of the invention as expressed in the claims. Therefore, we do not wish to be limited to all the details of construction herein shown and described, but what we claim is:—

1. The combination with a leather cutting machine having a block for supporting leather with the dies on it and a beam at the top parallel with the block for engaging the tops of the cutting dies, of a frame adapted to be mounted between the beam and the block in any desired position along the beam, a carriage slideable on said frame longitudinally of the beam, a slide transversely movable on the carriage across the machine and over the block, and a rotary cutting tool carried by the slide and movable therewith for dressing off the top of the block.

2. The combination with a leather cutting machine having a block and a beam, the lower surface of which is parallel with the upper surface of the block, of a frame secured to the bottom of the beam, a slide movable transversely on the frame across the machine over the block, a horizontal shaft carried by the slide, a cutting saw having an interrupted cylindrical surface fixed on said shaft, and means on the slide for rotating the saw.

3. The combination with a leather cutting machine having a block and a beam, of a frame mounted on said beam having end members provided with teeth along the bottom surface constituting a rack located at the front and back of the beam, a carriage supported by the end members and slideable

along them, a shaft extending across the carriage and having pinions meshing with said racks, whereby when the shaft is turned the carriage will move along the racks, means for turning the shaft by hand, and means supported by said carriage for planing off the top of said block.

4. The combination with a leather cutting machine having a block and a beam, of a frame on the lower surface of said beam and having parallel ways extending across the machine over the block, a slide supported

by said ways having a handle by which said slide can be moved back and forth, a motor carried by said slide having a shaft projecting beyond the slide at both ends, and a pair of Lamson saws on the ends of said shaft for planing off the top surface of said block. 15

In testimony whereof we have hereunto affixed our signatures.

ORNAN S. COOK.
HENRY A. GALE.
